RAILWAY TRAFFIC CONTROLLING
APPARATUSHoward A. Thompson, Edgewood, Pa., assignor to
The Union Switch & Signal Company, Swiss-
vale, Pa., a corporation of PennsylvaniaApplication October 16, 1930, Serial No. 489,065
Renewed March 18, 1933

33 Claims. (Cl. 246—33)

My invention relates to railway traffic controlling apparatus utilizing coded current in track circuits for the control of either or both wayside and cab signals in an absolute permissive block signaling system.

I will describe one form of apparatus embodying my invention and will then point out the novel features thereof in claims.

The accompanying Figs. 1^a, 1^b, 1^c and 1^d, when placed end to end with Fig. 1^a on the left, form a diagrammatic view showing one form of apparatus embodying my invention when applied to a stretch of single track railway extending between two passing sidings designated by the reference characters P1 and P2.

In describing my invention, reference is made to the accompanying drawings wherein like characters of reference designate corresponding parts with an exponent added to the reference character to designate the location. I shall assume the left-hand end of each figure to be west and the right-hand end of each figure to be east, and I shall speak of a train traveling from the right to the left as a westbound train and one traveling from the left to the right as an eastbound train.

The traffic rails 1 and 2 are arranged in track sections A—B, B—C, C—D, by the usual insulated rail joints. The track sections A—B and C—D are arranged with a cut section at the points A1 and D1 respectively. It will be understood however that arrangements of track sections other than that here disclosed may be employed without departing from the scope of my invention.

The energy for the operation of the apparatus is furnished by transformers L, one of which is located at each junction of adjacent track sections. The primary 4 of each of these transformers is connected to a transmission line E which is constantly supplied with alternating current of a convenient commercial frequency such as 60 cycles per second from a source not shown in the figures. An auxiliary transformer 45 M is located at each junction of adjacent track sections and its primary 5 is supplied with current from the secondary 6 of the associated line transformer L. A secondary 7 of each auxiliary transformer M is connected to the input terminals of a rectifier R which furnishes direct current for the operation of certain parts of apparatus of my invention.

Each track section is provided with a track circuit which includes a track transformer designated by the reference character T and a track

relay designated by the reference character TR. The secondary 16 of each track transformer is connected across the rails of the associated track section through the usual current limiting reactance 17. The primary 20 of each track transformer T is supplied with alternating current from an associated line transformer L which current is periodically interrupted or coded at the rate of 80 or 180 cycles per minute or any other code frequency desired under certain traffic conditions; while under other traffic conditions, the alternating current is non-coded, all of which will be fully described later on in the specifications. Each track relay TR is a two element relay having a track element 70 8 connected, in series with a secondary 9 of an impedance transformer 1T, across the rails of the track section at the end opposite from the track transformer. The second element 11 of each track relay is constantly supplied with alternating current from the secondary 6 of the associated line transformer L. Connected directly across the track leads of the track element 8 is the secondary 3 of a code feeding transformer CF in series with a current limiting reactance 10. Each track relay of my invention is so designed as to be responsive to code impulses received from the track circuit and connected in such a manner that it does not respond to the coded energy when supplied by 85 the associated code feeding transformer CF. The particular function of the track relay, the associated impedance transformer and the code feeding transformer will be brought out in detail as the description progresses. It follows 90 that when any given track section is unoccupied, the track relay of that section is normally operated by the 180 code alternating current supplied to the rails at the opposite end of the section.

At each junction of adjacent track sections, there is provided a code transmitter CT which includes a motor element 25 constantly supplied with alternating current by the secondary 6 of the line transformer L at that location. This 100 code transmitter is to be of any of the standard types commonly used and as here shown it will be understood that the four upper contacts (see Fig. 1^a) 35, 36, 37 and 38, periodically close their respective front and back contacts at a rate of 180 times per minute and that the four lower contacts 39, 40, 41 and 42 periodically close their respective front and back contacts at a rate of 80 times per minute.

Each track relay controls decoding apparatus 110

including a transformer DT, a rectifier DR and a decoding relay TP. The primary 43 (see location A of Fig. 1a) of each of the transformers DT is supplied with direct current by the associated rectifier R through an armature 44 of the track relay TR. When the track relay TR^A is energized, current from the positive terminal of rectifier R^A flows along wire 45, armature 44 in engagement with its front contact, the right-hand half of primary 43 of transformer 1DT^A to a center tap and wire 46 to the negative terminal of rectifier R^A. When relay TR^A is de-energized and armature 44 in engagement with its back contact, then current from rectifier R^A flows through the left-hand half of the primary 43 of transformer 1DT^A. It follows then that with the track relay TR^A operated by a coded current and its armature 44 alternately in engagement with its front and back contacts, an alternating voltage is induced in the secondary 47 of the transformer 1DT^A, the frequency being the same as the frequency of operation of a track relay, but when the track relay TR^A is continuously energized or is continuously de-energized, no voltage is induced in the secondary 47. The secondary 47 is connected to the input terminals of the rectifier 1DR^A, while the terminals of the decoding relay 1TP^A are connected to the output terminals of the rectifier 1DR^A as will be readily understood from the figure. The decoding circuit being non-tuned, it follows that with the track relay TR^A being alternately energized and deenergized in step with the 180 code, the relay 1TP^A is energized, while with the track relay TR^A remaining either continuously energized or deenergized, the decoding relay 1TP^A is deenergized.

At each junction of adjacent track sections, there is provided for each direction of traffic, a slow-acting relay designated by the reference character 1P where the relay is associated with eastbound traffic and 2P where the relay is associated with the westbound traffic. Referring to the slow-acting relay 1PA, current to energized this relay is supplied by the secondary 6 of the line transformer L^A over a circuit consisting of wires 12 and 57, armature 58 of the relay 1TP^A, wire 59, armature 60 of a line control relay 1H^A to be referred to later, wire 61, relay 1PA and wires 62 and 14 to the common terminal of the secondary 6. All slow-acting relays of my invention are controlled by a circuit similar to that just traced for the slow-acting relay 1PA, except for a slight modification at all intermediate signals as will shortly be pointed out.

At all intermediate locations, the slow-acting relays 1P and 2P are associated with a thermal unit TU, which retards the pick-up of the relay and which is connected into the circuit whenever the relay is deenergized. Referring to the relay 1PC of Fig. 1^c, it is to be noted that this relay is normally held energized by a circuit including a back contact 145 of the opposing directional relay 2V^C and the front contact of its own armature 63. To close this stick circuit for relay 1PC it is required that the associated thermal unit 1TU^C must first be heated to close the contact 65. As soon as the heating element 66 heats up so as to close contact 65, a pick-up circuit is established through the contact 65 to the relay 1PC. With relay 1PC once up, it closes its stick circuit at the front contact of armature 63 and opens the circuit to the heat-

ing element 66 at the back contact of armature 63.

At the junction of adjacent intermediate track sections, there are provided two directional stick relays designated by the reference character 1V and 2V with an exponent corresponding to the location. These stick relays perform similar functions to those performed by the directional stick relays used in standard absolute permissive block systems—that is, to establish directional control and to permit following train movements. As the circuit for selecting the directional relay is the same at each location of my invention, only one location will be described. Referring to location C of Fig. 1^c, directional relay 1VC has a pick-up circuit consisting of secondary 6 of the line transformer L^C, wire 67, armature 68 of the relay 2PC down in engagement with its back contact, wire 69, armature 70 of relay 2TP^C down in engagement with its back contact, wire 71, armature 72 down in engagement with its back contact, wire 73, armature 74 in engagement with its front contact, wire 75, relay 1VC and wire 76 to the common terminal of secondary 6. The stick circuit for this directional relay 1VC extends from the wire 67 along wire 77, armature 78 of relay 1TP^C in engagement with its back contact, wire 79, armature 80 of relay 1VC up in engagement with its front contact and wire 81 to the wire 75 and then to the coil of the relay 1VC. There exists also a second path for this stick circuit for relay 1VC that branches from wire 67, through back contact 144 of relay 1PC and to the wire 79.

At the junction of adjacent track sections there is also provided for each direction of traffic a line control relay. The line control relays associated with traffic from the left to the right in the figures are designated by the reference character 1H with an exponent corresponding to the location; while the relays associated with traffic from the right to the left are designated by the reference character 2H with an exponent corresponding to the location. Each of these line control relays is a three position polarized relay governing the operation of an associated wayside signal in accordance with standard A. P. E. signaling. Referring to the line control relay 1H^A, the element 48 is constantly supplied with alternating current from the secondary 6 of the transformer L^A by means of wires 12 and 13 on one side and by wire 14 to the other terminal. The second element 49 of the relay 1H^A is normally supplied with alternating current from the secondary 6 of the transformer L^B by the circuit that extends from one terminal of the secondary 6 of L^B along wire 50, armature 51 of relay 1PB, wire 52, armature 53, line wire 54, element 49, wire 14, common line wire 18 and wire 56 to the other terminal of secondary 6 of L^B.

Under normal or clear traffic conditions, the instantaneous polarity of the current energizing the two elements 48 and 49 of relay 1H^A is such as to cause the contact armatures of the relay 1H^A to swing to the left—that is, to the position shown in the Fig. 1^a. With the relay 1PB deenergized so that its armature 51 is in engagement with its back contact and with the directional relay 1VB energized so that its armature 82 is up in engagement with its front contact, the element 49 of relay 1H^A is supplied with current by a circuit extending from the center terminal of winding 5 of the transformer M^B 150

- along wire 56, common line wire 18, wire 14, element 49, line wire 54, armature 53, wire 52, armature 51, wire 83, armature 82 and wire 84 to a negative terminal of the winding 5 of transformer M^B . Under this condition and with the winding 5 of M^B functioning as an auto transformer, the instantaneous polarity of the current energizing element 49 of relay $1H^A$ is opposite to that of the current energizing the element 48 and it follows that the contact armatures of the relay $1H^A$ will be reversed to the right-hand position—that is, a position opposite to that shown in the Fig. 1^a. It will be understood that with either element 48 or 49 deenergized,—the armatures of the relay $1H^A$ will assume a vertical or mid-position. Each line relay of my invention is controlled in a manner similar to that just described for the relay $1H^A$.
- Each track section is provided with a wayside signal located at each end of the section and these signals govern traffic in opposite directions through the section. Signals governing traffic from the left to the right in the figures are designated by the reference character 1S with an exponent corresponding to the location, while the signals governing traffic from the right to the left are designated by the reference character 2S with an exponent corresponding to the location. These wayside signals may be of any standard type and are here shown as the three-position light signal type. The lighting circuits of each signal are controlled by the associated line control relay and as the lighting circuits of all signals are alike, a description of any one will be sufficient for the understanding of all. Referring to the signal 1S^A, the proceed light circuit extends from one terminal of secondary 6 of transformer L^A along wires 12, 26 and 86, armature 87 of relay 1PA raised into engagement with its front contact, wire 88, armature 89 of the line control relay $1H^A$ in the left-hand position, wire 90, proceed light 91 of signal 1S^A and wires 92 and 14 to the common terminal of the secondary 6. The caution light circuit is the same as that just traced for the proceed circuit up to the armature 89, and with armature 89 in the right-hand position it extends along wire 93, caution light 94 and wires 92 and 14 to the common terminal of 6. The stop light circuit is the same as that traced for the proceed light up to armature 87 and then with armature 87 down in engagement with its back contact, it extends along wire 95, stop light 96 and wires 92 and 14 to the common terminal of 6.
- At intermediate track sections equipped with but one track circuit such as the track section B—C, a slow-release floating track relay N^B is provided in order to provide proper operation of the directional stick relays at that location. A transformer 97 has its primary 98 connected across the track leads of the track transformer T^B , while the secondary 99 of the transformer 97 is connected to the input terminals of the rectifier 100, the output terminals of which are connected to the relay N^B . Relay N^B being slow-releasing, it follows that its armature will remain lifted so long as the primary of a track transformer T^B is fed with coded energy or with non-coded alternating current, but with the transformer T^B not supplied with energy, then the relay N^B becomes deenergized.
- Having pointed out the various devices with which my invention is provided, I will now de-
- scribe its operation and I shall first assume that all track sections between the two sidings are unoccupied. Normally coded alternating current is supplied to each track circuit by the track transformer. Referring to the track circuit for the section A—A₁, the primary 20 of the track transformer TA1 has one terminal connected to the common terminal of secondary 6 of the line transformer L^A by the common line wire 18 and wire 14, while the other terminal of the primary 20 is connected to the other side of the secondary 6 by the line wire 22, armature 23 of the relay 1TP^A, wire 24, 180 code contact 38 of the code transmitter CT^A and wires 26 and 12. It follows then that the track relay TR^A normally follows each 180 code cycle, alternately closing the front and back contacts of its armature 44. As pointed out earlier in the description, the positive terminal of the rectifier R^A is connected to the heel of the armature 44 by a wire 45 and the extreme ends of the primary 43 of the decoding transformer 1DT^A are connected to the front and back contacts of the armature 44; while the center tap of the primary 43 is connected to the negative terminal of the rectifier R^A by a wire 46. Therefore with armature 44 alternately closing its front and back contacts, the half of the primary winding of the decoding transformer fed by the front contact will be energized for the duration of the "on" code period building up a flux in one direction and when the "off" period of the code cycle occurs and the back contact closes, the other half of the primary 43 will be energized in a reverse direction from that of the first. This action will cause the flux to build up in the first instance and to die down and build up in the reverse direction with each 180 code cycle. With the building up of the flux in one direction and the dying down and building up in the opposite direction, a voltage is induced in the secondary 47 of the transformer 1DT^A said voltage having a corresponding frequency. As the secondary 47 is connected to the input terminals of a rectifier 1DR^A to whose output terminals the relay 1TP^A is connected, and, inasmuch as the circuit is non-tuned, the relay 1TP^A is normally energized. With relay 1TP^A normally energized so that its armature 58 is in engagement with its front contact, the circuit to the relay 1PA is held closed and thus the relay 1PA is also normally energized. Inasmuch as all track circuits function alike, we see, therefore, that the track circuit of each track section is normally supplied with 180 code energy and that this energy is decoded to energize the TP relay and in turn permits the energizing of the 1P or the 2P relay at that location. It will be noted that the circuit for the primary 20 of the track transformer TA1 is controlled by the front contact of the armature 23 of the decoding relay 1TP^A which in turn is controlled by the track circuit fed by this track transformer. It follows then that once the track circuit to the primary of the track transformer is opened it must be closed by a path around the front contact of the armature 23. Assuming that the track circuit for the section A—A₁ has been shunted and that the relay 1TP^A is deenergized as the result thereof, we find that with the armature 23 in engagement with its back contact that a circuit is established from the wire 22 along wire 101, armature 28 of the line control relay $1H^A$ in the normal position, wire 29 to the 180 code contact 38 of the code transmitter CT^A.

Or in the event that traffic conditions are such that the line relay $1H^A$ is reversed and armature 28 is in engagement with its reverse contact then this circuit extends along the wire 32, to the 80 5 code contact 42 of the code transmitter CT^A . Again, in the event the line relay $1H^A$ is deenergized and its armatures occupy a mid-position, then the circuit extends from the wire 101 along wire 31, armature 30, wires 33, 26 and 12 directly 10 to the secondary 6 of the transformer L^A . It will thus be seen that the track circuit for the section A—A1 when unoccupied is continuously supplied with 180 code energy and that once the track section becomes occupied then the current 15 supplied to the track circuit may be either continuous alternating current, or 80 code current, or 180 code current as governed by the line control relay in accordance with the different traffic conditions to be later described.

20 Referring to the impedance transformer $1T^A$ and the code feeding transformer CF^A associated with the track relay TR^A , the wire 103 is permanently connected to one side of the primary 104 of the code feeding transformer CF^A 25 and also to one side of the primary 105 of the impedance transformer $1T^A$ and this wire 103 connects these transformers to the heel of the armature 106 of the decoding relay $1TP^A$. The opposite side of the primary 104 is permanently 30 connected to the common terminal of the secondary 6 of the line transformer L^A by the wire 14. As long as the section A—A1 is unoccupied so that the relay $1TP^A$ is energized, these transformers $1T^A$ and CF^A are connected through the 35 front contact of the armature 106 and a wire 107 to the 180 code contact 36 of CT^A and thence by wires 26 and 12 to the other terminal of the secondary 6. It is to be noted that the other terminal of the primary 105 of $1T^A$ is 40 connected to the back contact of 180 code contact 36 by the wire 108. The 180 code contact 36 operates in unison with the 180 code contact 38 which feeds coded energy to the primary 20 of the track transformer $TA1$. When the 45 code contacts 36 and 38 are in their upper position, wire 107 is connected to the secondary 6 and when contacts 36 and 38 are in their lower position this wire 107 is connected to wire 108 and the primary 105 is thereby short-circuited. 50 Thus when the code transmitter is in its upper position, energy is fed to the primary winding 104 of the code feeding transformer CF^A , the primary 105 of the impedance transformer $1T^A$ is open circuited, and the primary 20 of the track transformer $TA1$ is also open circuited. 55 When the code transmitter is in its down position, the primary 20 of the track transformer $TA1$ is receiving energy, the primary 104 of the code feeding transformer CF^A is disconnected and the primary 105 of the impedance transformer $1T^A$ is short-circuited so that the energy from the secondary 20 of the track transformer $TA1$ may flow freely to the winding 8 of the track relay TR^A to energize that relay. When 60 the code transmitter CT^A is in its up position and the secondary 3 of the code feeding transformer CF^A is supplying energy to the rails, the primary 105 of transformer $1T^A$ is open circuited and thus the secondary 9 offers relatively high impedance to the flow of energy from the secondary 3 through the element 8 of the track relay TR^A . Furthermore the current supplied by the secondary 3 to the track leads is in the reverse direction from that supplied by the normal track transformer $TA1$.

and it follows that whatever small energy reaches the element 8 from the secondary 3 is in a direction to open the relay TR^A .

With the relay $1TP^A$ deenergized so that the armature 106 is in engagement with its back contact, the primary 104 of CF^A is supplied with 80 180 code energy over a circuit from the secondary 6 of line transformer L^A , wires 12 and 26, 180 code contact 36, wire 109, normal contact of the armature 110 of line control relay $2H^A$, wire 111, armature 112 of relay $2PA$, wire 113, back contact of the armature 106, wire 103, primary 104 and wire 14 to the common terminal of the secondary 6. In the event 85 that traffic conditions are such that the line control relay $2H^A$ is reversed and its armature 110 in engagement with its reverse contact or that the armature 112 of the relay $2PA$ is in engagement with its back contact, then the code feeding transformer CF^A is supplied with 90 80 code energy through the 80 code contact 40 of the code transmitter CT^A , along the wire 114, armature 112 and wire 113, and then as before traced, or else by the 80 code contact 40 along wire 114, armature 110 reversed, wire 111, 100 armature 112 up, wire 113 and as before traced.

With each track circuit supplied with coded energy at each end of the section in a manner similar to that just described for the track circuit of section A—A1, it becomes apparent 105 that the coded track current affords a means for controlling wayside signals governing traffic in either direction. It also affords means for supplying cab signal controlling current to the rails to control train carried apparatus receiving current inductively from the track rails such as the apparatus described and claimed in the Letters Patent of the United States, No. 1,773,472 filed by P. N. Bossart on the 7th day 110 of February, 1927.

I will not describe the operation of the apparatus for a train moving from the left to the right—that is, an eastbound train and I shall assume that the train occupies the track section to the left of a location A and that the intermediate sections to the passing siding P2 are all 115 unoccupied. With the train occupying the track circuit to the left of A, the slow acting relay $2PA$ is deenergized with the result that the signal $2S^A$ indicates stop and the signal $2S^B$ indicates 120 caution. As the train advances to the right and enters the track circuit A—A1, the track relay TR^A and in turn relays $1TP^A$ and $1PA$ all become deenergized and the wayside signal $1S^A$ is caused to display a stop signal. The deenergization of the $1TP^A$ relay opens the line circuit for the line control relay $2H^B$ at the front contact of armature 115 and thus the signal $2S^B$ is set at stop. In like manner each successive westbound signal up to the passing siding 125 P2 is set at stop. The track transformer $TA1$ will continue to supply to the rails of A—A1, 180 code energy by a circuit extending from the secondary 6 of L^A along wires 12 and 26, 180 code contact 38, wire 24, wire 29, armature 130 28, wire 101, armature 23, wire 22, primary 20, common line wire 18 and wire 14 to the common terminal of secondary 6. This 180 code energy in the rails of the section A—A1 will establish a proceed cab signal on the train. As the train 135 advances and passes the cut section A1 and enters the track circuit of A1—B, it shunts the track relay TR^B and in turn the relay TP^B is deenergized with the result that the line control relay $1H^A$ now becomes deenergized due to its 140 145 150

line circuit being opened at the armature 53 and thus the wayside signal 1S^A still displays a stop signal. The deenergization of relay 1H^A cuts off 180 code energy fed to transformer TA1 at the 5 contact 28. The code feeding transformer CF^B now supplies the rails of A1-B with 180 code energy to establish a proceed cab signal. The circuit by which the code feeding transformer CF^B supplies 180 code energy to the rails of 10 A1-B is from the secondary 6 of the transformer LB, wire 50, 180 code contact 35 of CT^B, wire 117, armature 118, wire 119, armature 120, in engagement with its back contact, wire 121, primary 122 of code feeding transformer CF^B 15 and wires 123 and 56 to the other terminal of the secondary 6.

It is to be noted that when the relay 1TP^A is deenergized, the primary 105 of the impedance transformer 1T^A is short-circuited through a 20 back contact of the code transmitter CT^A by a shunt path extending from primary 105 along wire 103, back contact of the armature 106 of relay 1TP^A, wire 113, armature 112 in its raised position, wire 111, armature 110 of the line relay 25 2H^A, wire 109, back contact of the 180 code contact 36 and wire 108 to the other terminal of the primary 105. In the event that the relay 2PA is down, then the shunt extends from the armature 112 along wire 114, back contact of the 30 80 code contact 40 and to wire 108. In the case where armature 112 is up and the armature 110 of relay 2H^A is reversed, then this shunt path also is by way of the back contact of the 80 code contact 40.

As the train vacates the section A-A1, non-coded alternating current is supplied to the transformer TA1 by a circuit as follows: secondary 6 of transformer LB, wires 12, 26 and 33, deenergized contact of armature 30 of relay 1H^A, wires 31 and 101, back contact 23, wire 22, primary 20 of transformer TA1 and wires 18 and 14 to the other terminal of the secondary 6. This non-coded alternating current flows in the track element 8 of the relay TR^A and due to the periodic shunting of the primary 105 of the impedance transformer 1T^A by one of the paths just traced and which paths include a code contact of the code transmitter CT^A, it follows that the current value in the element 8 will be periodically varied. When the shunt is closed, the secondary 9 of 1T^A offers relatively low impedance and the current in 8 is of sufficient value to lift the armature 44 of the relay TR^A. When the shunt is opened at the code 45 contact of transmitter CT^A, the secondary 9 offers a relatively high impedance and the current in the element 8 is reduced to a value where the armature 44 drops. Thus by this varying of the effective impedance of the secondary 9, track relay TR^A is caused to operate on code although the track transformer TA1 supplies non-coded current to the track circuit. After a few operations of the armature 44, the decoding relay 1TP^A is reenergized and as soon as its armature 23 is lifted, 180 code current is supplied to the track transformer TA1, as under normal conditions. Any following eastbound train that might enter the section A-A1 while the first eastbound train occupies the 50 section A1-B will receive only non-coded alternating current. The energization of the relay 1TP^A closes the front contact at the armature 154 with the result that current is then fed to the line circuit for the eastbound signal 55 to the rear of signal 1S^A and this signal to the

rear of 1S^A will thus display an approach signal as soon as the track section A-A1 is vacated.

As the train enters the section B-C, the track relay 1TR^C is shunted and the track repeater relay 2TP^C is deenergized to open the line circuit to the primary of the track transformer TB at the front contact of the armature 124. The floater relay N^B being also shunted, becomes deenergized and closes the back contact of the armature 125. The line control relay 1H^B and the repeater relay 1PB both become deenergized when the track circuit of B-C is shunted. It is arranged that the relay N^B will drop and closes the back contact 125 before the armatures of the relay 1PB disengage their front contacts and thus the pick-up circuit for the directional relay 1V^B becomes closed. The pick-up circuit for the directional relay 1V^B is similar to that traced earlier in the description for the directional relay 1V^C. With the directional relay 1V^B once up, then its stick circuit is closed and the relay remains energized after the relay 1PB drops. This deenergization of the line relay 1H^B and the picking up of the directional 100 relay 1V^B results in the signal 1S^B displaying a stop indication and the signal 1S^A displaying an approach indication.

As the train enters the section B-C, the primary 146 of the impedance transformer 1T^B 105 is short-circuited by a shunt path extending from one side of the primary 146 along wire 121, back contact of the armature 120 of the relay TP^B, wire 119, back contact of the armature 118 of the relay 1PB, wire 143, front contact of armature 142, wire 141, back contact of 110 80 code contact 39 of the code transmitter CT^B and wire 147 to the opposite terminal of the primary 146. As the train vacates section A1-B, the line relay 2H^B having been reenergized, coded energy is supplied to the track transformer TB1 through the back contact 130 of the decoding relay TP^B and the polar armature 155 of the line relay 2H^B. The track relay TR^B is now operated on code in as much as a code 120 impulse will occur during the interval that the primary 146 is short-circuited and thus the relay TP^B is reenergized with the result that the normal circuit for supplying 180 code energy to the track transformer TB1 is restored. In 125 the event that a second eastbound train is following, the second train holding the line relay 2H^B deenergized, then non-coded energy is supplied to the transformer TB1 after the first train vacates the section A1-B, the circuit 130 being from the secondary 6 of the transformer LB along wire 50, deenergized contact of the armature 126, wire 127, back contact of the armature 128, wire 129, back contact of the armature 130, line wire 131, primary 20 of transformer TB1, the common line wire 18 and wire 56 to the other terminal of the secondary 6. Due to the above described shunt path on the primary 146 of the impedance transformer 1T^B, the secondary 9 of the transformer 1T^B offers 135 low impedance to the non-coded current supplied to the track element of the track relay TR^B, during the period that the shunt path is closed at the 80 code contact 39, and a relatively high impedance during the period that the shunt is opened. It follows that the track relay TR^B will be operated on code as the result of the variation of the effective impedance of the secondary 9 and thus the track relay will 140 operate to reenergize the decoding relay TP^B 150

in the same manner as that described for the relay TR^A . The reenergization of the decoding relay TP^B restores the normal circuit by which 180 code is fed to the transformer $TB1$. It is 5 to be noted that the circuit for supplying non-coded energy to the transformer $TB1$ includes a back contact of the 128 armature of the relay TR^B . The energization of the relay TR^B during the interval that the shunt on the transformer $1T^B$ is closed will act to open this circuit 10 for supplying non-coded energy to the track transformer at the armature 128 and this action will also produce an alternate raising and dropping of the armature of the track relay TR^B 15 to thereby assist in the prompt energization of the decoding relay TP^B . This last feature however is used further under westbound traffic conditions as will be pointed out later. As the relay TP^B is reenergized and the armature 120 20 raised, the shunt on the primary 146 that was previously traced is disconnected and the primary 146 is alternately opened and closed at a back contact of the 180 code contact 35 of the code transmitter CT^B as is done under the 25 normal condition of the track circuit.

As the eastbound train vacates the section B—C, the line relay $2H^C$ having become energized, coded current is supplied to the track transformer TB for the section B—C. This circuit 30 includes a back contact of the armature 124 of the relay $2TP^C$ and the armature 156 of the relay $2H^C$, and thus the track circuit for the section B—C is restored to 180 code energy. In the event that there is a following 35 eastbound train and the relay $2H^C$ is held deenergized, then non-coded current is supplied to the track transformer TB after the first train vacates the section B—C. However, the train 40 by shunting the track circuit of the section C—D1 provides a shunt path on the primary of the impedance transformer $1T^C$ which shunt path is similar to that traced for the transformer $1T^B$ and which includes a contact of the code transmitter CT^C . The result is that in this case 45 the relay $1TR^C$ is operated by means of varying the effective impedance of the transformer $1T^C$ in the same manner as has been previously described for the track relays TR^A and TR^B with the result that the track circuit for the 50 section B—C is restored to 180 code energy.

As the train travels in the section B—C, 180 code energy is supplied to the rails by the code feeding transformer CF^C over a circuit extending 55 from the secondary 6 of the line transformer L^C along wire 67, 180 code contact 35 of code transmitter CT^C , wire 133, armature 134, wire 135, back contact of armature 136, wire 137, primary of the code feeding transformer CF^C and wire 138 back to the secondary 6 and this 60 180 code energy will establish a proceed cab signal. I have above pointed out how a caution signal is displayed by the wayside signal $1S^A$ during the time that the train occupies the track section B—C. In the event that a following train enters the section A—A1 and shunts TR^A to drop relay $1TP^A$, 80 code energy is supplied to the rails by the track transformer $TA1$ by a circuit previously traced and which includes the 65 80 code contact 42 of the code transmitter CT^A and the reverse contact of the armature 28 of the line control relay $1H^A$. Thus as this following train enters and travels in the section A—A1, 80 code energy is supplied to establish a caution cab signal. Should the following train advance and 70 enter the section A1—B while the first train still

occupies the section B—C then 80 code energy is supplied to the rails of the section A1—B by the code feeding transformer CF^B over a circuit extending from the secondary 6 of transformer L^B along wire 50, 80 code contact 39 of code transmitter CT^B , wire 141, armature 142 in engagement with the front contact, wire 143, armature 118, wire 119, armature 120, wire 121, primary 122 and wires 123 and 56 back to the secondary 6. This 80 code energy supplied to the rails of the section A1—B will establish a caution cab signal on this following train. 80

As the train which I have assumed to be traveling from the left to the right travels in the successive track sections, the operation will be 85 similar to that described in connection with the track sections A—B and B—C. 90

To sum up the operation of an eastbound train, it is found that as the train enters each section, coded alternating current is applied to 95 the rails at the exit end of the section to effect operation of the cab signals, this coded current being of a code determined by traffic conditions in advance. The track circuits are restored either by applying coded current as soon 100 as the train vacates the section or, in the event that there is a second train following, by applying non-coded current to the rails and then varying the impedance of the circuit at the relay end which effects the resetting of the track circuit. All opposing wayside signals in advance 105 of the train are held at stop, and the eastbound signals to the rear of the train are governed according to the usual practice.

The operation of the apparatus as a westbound train travels from the passing siding $P1$ is similar to that described for the operation of the eastbound train, except for certain differences in the method of resetting the track circuits which 110 will now be pointed out. 115

Assuming that a westbound train travels in the section B—C, the normal active transformer TB will supply coded current to the rails to effect operation of the cab carried devices. As 120 the westbound train vacates the section B—C and effects the deenergization of the line relay $2H^C$, non-coded alternating current will be supplied to the transformer TB . In the event that there is no following westbound train, the relay $1PC$ will have been picked up as the train vacated the section C—D1 and with the relay $1PC$ up to close the front contact of the armature 134 there exists a shunt path around the primary of the impedance transformer $1T^C$ that 125 includes wire 152, the 180 code contact 35 of the code transmitter CT^C , wire 133, armature 134, wire 135, armature 136 down and wire 137. The periodic opening and closing of this shunt path at the 180 code contact 35 brings about 130 the operation of the track relay $1TR^C$ by the non-coded current being supplied by the track transformer TB . As a result, the decoding relay $2TP^C$ is reenergized and the track circuit for section B—C restored to 180 code energy. In 135 140 the event that a second westbound train is following and the relay $1PC$ is deenergized thereby, a shunt is placed around the primary of $1T^C$ that includes wire 152, armature 153 of $1VC$ down, armature 134 down, wire 135, armature 136 145 down and wire 137. Inasmuch as this shunt path is not periodically opened and closed, the non-coded current supplied to the transformer TB would pick up the relay $1TR^C$ and hold it up were it not for the fact that the circuit for 150

supplying the non-coded current to the transformer TB includes the back contact of the 128 armature of the relay 1TR^C. The result is that the pickup circuit for relay 1TR^C is opened once this relay is energized. It follows that the armature of the relay 1TR^C will be alternately lifted and dropped. After a few such operations, the decoding relay will be energized and once it is energized, the track circuit is restored to 180 code energy. The restoring of the track circuit for the section A1—B to 180 code energy as the westbound train travels and vacates that section will be similar to that just described for the section B—C.

As the westbound train vacates the section A—A1, the relay 1H^A will be reenergized if there is no following train and with 1H^A energized, coded energy is at once supplied to the transformer TA1 with the result that the decoding relay 1TP^A is reenergized and the circuit restored to its normal condition. If there is a following westbound train and the relay 1H^A is deenergized thereby, then non-coded energy is supplied to the transformer TA1. There exists however, a shunt path on the primary of 1T^A that includes the 80 code contact 40 of the code transmitter CT^A and a back contact of the armature 112 of the relay 2PA. The periodic variation of the impedance of the secondary 9 by the opening and closing of this shunt path will produce an operation of the track relay TR^A that reenergizes the decoding relay 1TP^A and restores the track circuit of section A—A1 to 180 code.

To sum up the operation for westbound traffic, it is found that coded energy is supplied at the exit end of each track section to effect operation of the train carried cab signals. By means of the line relay H, the opposing eastbound signals in advance of the train are held at stop. The track circuits are restored to the normal condition of 180 code energy either by supplying coded energy as soon as the track section is vacated or in the event that there is a following train by first applying non-coded current and periodically interrupting the circuit or else by varying the effective impedance of the track circuit at the relay end.

Such a system herein disclosed and described is practically immune from propulsion alternating current or direct current, or any other form of electrical energy that may be used in the running rails. Furthermore, such a system will operate equally as well for wayside signals alone or train-carried cab signals alone or for both wayside and cab signals.

It will be understood that the train governing rail current which I use for the purpose of train detection, that is, for the purpose of indicating the presence or absence of a train within a track section by means of wayside equipment, as well as the rail current which I use for the control of cab signals, are not confined to alternating current, nor to current of the periodically interrupted type. Obviously, the coded current used for detection and cab signal control may be either alternating or direct, the only requirement being that the periodic variations in this current be of such character as to permit the code following track relay to follow, and at the same time to produce suitable response of the cab signaling devices on the train.

Although the 180 code which I use for detection purposes is the same as the 180 code used for clear cab signals, it will be understood that

any other code suitable for operating the code following track relays may be used. That is, a separate and distinct code may be used for detection purposes, use of the 180 code for this purpose being made primarily to avoid the necessity for additional apparatus such as code transmitter and relay contacts. Since the track relays are sufficiently quick acting to follow the fastest of the cab signal codes, a reset or transfer from the cab signal code to the detection code may be obtained on any of the cab signal control codes, as determined by traffic conditions. The cab signal control code can, of course, be used to operate any train-carried governing devices other than cab signals, or in addition thereto. For example, this code may be used to control speed governing apparatus, if desired.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a track section, a wayside signal located at each end of the section to govern traffic in opposite directions through the section, a line relay for each signal to govern the operation of the signal, means to normally supply to the rails of the section train governing alternating current periodically interrupted, a track relay connected to the rails and responsive to such periodically interrupted alternating current, a decoding relay, means associated with the track relay to energize said decoding relay when the track relay is operated by the interrupted alternating current, and means responsive to the energizing of the decoding relay to render each line relay effective to clear its associated wayside signal.

2. In combination, a track section, a wayside signal located at each end of the section to govern traffic in opposite directions through the section, a line circuit for each signal, a circuit controlling device controlled by each line circuit to govern the operation of the associated signal, means to normally supply to the rails of the section train governing alternating current periodically interrupted, a track relay connected to the rails and responsive to such periodically interrupted alternating current, a decoding relay, means associated with the track relay to energize the decoding relay when the track relay is operated by the interrupted alternating current, and means responsive to the energizing of the decoding relay to render each circuit controlling device effective to clear its associated signal.

3. In combination, a track section, a track circuit for said section including the traffic rails, means located at the exit end of the section to normally supply alternating current periodically interrupted at different rates to the track circuit, a track relay connected to the rails and normally responsive to said periodically interrupted alternating current, a polarized line relay, means controlled by the track relay of another track section to effect normal and reverse positions of said line relay, and a polarized armature controlled by the polarized line relay to select the different rates of the periodically interrupted current.

4. In combination, a track section, a track

circuit for said section including the traffic rails, means to normally supply alternating current periodically interrupted to the track circuit, a track relay connected to the rails and normally

- 5 responsive to said periodically interrupted alternating current, a decoding relay, means associated with the track relay to energize the decoding relay when the track relay is operated by the interrupted alternating current, a polarized line relay, means controlled by the decoding relay of another track section to effect normal and reverse positions of said line relay, a wayside signal having a proceed and a caution operating circuit, and a polarized armature controlled by the polarized line relay to selectively control the operating circuits.
- 10

5. In combination, a track section, a track circuit for said section including the traffic rails, means to normally supply alternating current periodically interrupted at different rates to the track circuit, a track relay connected to the rails and normally responsive to said periodically interrupted alternating current, a decoding relay, means associated with the track relay to energize the decoding relay when the track relay is operated by interrupted alternating current of any one of said different rates, a polarized line relay, means controlled by the decoding relay of another track section to effect normal and reverse positions of said line relay, a wayside signal having a proceed and a caution operating circuit, a first polarized armature controlled by the polarized line relay to selectively control the operating circuits, and a second polarized armature controlled by the line relay to select the different rates of the periodically interrupted current.
- 20

6. A combined wayside and cab signal system for railways including, a track section, two wayside signals located so as to govern traffic in opposite directions through the section, a line circuit for each wayside signal to control the operation of the signal, means at each end of the section to normally supply to the rails train-governing alternating current periodically interrupted at different rates, a track relay responsive to such interrupted alternating current and connected to the rails at one end of the section, means to permit the operation of said track relay by the interrupted alternating current supplied to the rails at the end opposite the relay and to prevent its operation by the interrupted current supplied to the rails at the same end as the relay, decoding means controlled by the track relay when operated by the interrupted current to control the said line circuits, and means rendered effective by a train traveling through the section in either direction to select the rate of interruptions of the alternating current supplied to the rails at the end in advance of the train in accordance with traffic conditions ahead.
- 25

7. A combined wayside and cab signal system for railways including a track section, two wayside signals located so as to govern traffic in opposite directions through the section, a line circuit for each wayside signal to control the operation of the signal, means at each end of the section to normally supply to the rails coded alternating current of codes to produce different cab indications, a track relay responsive to coded alternating current and connected to the rails at one end of the section, means to permit the operation of said track relay by the coded alternating current supplied to the rails at the end opposite the relay and to prevent its operation
- 30

of the relay by the coded current supplied to the rails at the same end as the relay, decoding means controlled by the track relay when operated by coded alternating current to control the said line circuits and thereby control the wayside signals, and means rendered effective by a train traveling through the section in either direction to select the code supplied to the rails at the end in advance of the train in accordance with traffic conditions ahead and thereby control train carried cab signals.

35

8. A combined wayside and cab signal system for railways including, a track section, two wayside signals located so as to govern traffic in opposite directions through the track section, means at each end of the section to supply to the rails alternating current periodically interrupted at different rates to produce different cab indications, a track relay connected to the rails at one end of the section and responsive to such periodically interrupted alternating current, means to normally permit the operation of the track relay by the interrupted current supplied to the rails at the end opposite the relay and to prevent the operation of the track relay by the interrupted current supplied to the rails at the same end as the relay, a decoding relay, means associated with the track relay to energize the decoding relay when the track relay is operated by interrupted alternating current of any one of said different rates, means rendered effective with the decoding relay energized to govern the operation of each of said wayside signals; and two means, one for each direction of traffic each of which is responsive to traffic conditions in advance of the track section for its respective given direction of traffic, and rendered effective with the decoding relay deenergized to select the rate of the periodically interrupted alternating current supplied to the rails at the exit end of the track section for its respective direction of traffic and thereby selectively control train-carried cab signals.

90

9. A railway signal system, including a stretch of single track railway arranged in track sections, a first signal located at one end of the stretch to govern traffic in one direction through the stretch, a second signal located at the other end of the stretch to govern traffic in the other direction through the stretch, a line circuit for each signal to control the operation of the signal, a source of train governing coded alternating current for each section located at one end and arranged to normally supply coded alternating current to the rails, a track relay for each section connected to the rails at the end opposite the source and responsive to coded alternating current, a decoding relay for each section, means associated with each track relay to energize the decoding relay of the section in response to the track relay operated by the coded alternating current, and means controlled by each decoding relay to control the line circuit of each of said signals.

95

10. A railway signal system including a stretch of single track railway arranged in track sections, a first signal located at one end of the stretch to govern traffic in one direction through the stretch, a second signal located at the other end of the stretch to govern traffic in the other direction through the stretch, a line circuit for each signal to control the operation of the signal normally closed to establish a proceed signal, a source of train governing coded alternating current located at each end of each

- section each arranged to normally supply coded alternating current to the rails, a track relay for each section responsive to coded alternating current and connected to the rails at one end of the section, means to normally permit operation of the track relay of each section by the coded alternating current supplied to the rails at the end opposite the relay and to prevent the operation of the relay by the coded alternating current supplied to the rails at the same end as the relay, and means controlled by each track relay to control the line circuit of said signals and to control the supply of train governing coded alternating current at each end of the associated track section. 80
11. A railway signal system including a stretch of single track railway arranged in track sections, a signal located at each end of the stretch to govern traffic in opposite directions through the stretch, a line circuit for each signal to control the operation of the signal normally closed to establish a proceed signal, a source of train governing coded alternating current located at each end of each section each arranged to normally supply coded alternating current to the rails, a track relay for each section responsive to coded alternating current and connected to the rails at one end of the section, means to normally permit the operation of the track relay of each section by the coded current supplied to the rails at the end opposite the relay and to prevent the operation of the relay by the coded current supplied to the rails at the same end as the relay, and means controlled by the track relay of a section effective when a train occupies the section traveling in either direction to open the line circuit of the opposing signal and to discontinue the normal supply of the train governing coded alternating current to the rails at the exit end of each track section for a train traveling in the opposite direction. 95
12. In combination, a track section, two way-side signals located so as to govern traffic in opposite directions through the section, a line relay for each signal, a slow acting relay associated with each line relay, means jointly controlled by a line relay and its associated slow acting relay to govern the operation of the associated signal, a source of current located at each end of the track section, coding means associated with each current source each adapted to normally supply train governing coded current to the rails of the section, a track relay responsive to such coded current and connected to the rails at one end of the section, means to normally operate the track relay by the coded current supplied to the rails at the end opposite the relay and to prevent the operation of the relay by the coded current supplied to the rails at the same end as the relay, a decoding relay, means to energize the decoding relay in response to the track relay operated by coded current, a first circuit means controlled by the decoding relay to control the slow acting relay located at the same end as the track relay and the line relay located at the opposite end to thereby control the signals, and a second circuit means controlled by the decoding relay to control the supply of train governing coded current at each end of the track section. 100
13. In combination, a track section over which traffic may move in either direction, a signal located at each end of the section to govern traffic in opposite directions through the section, a line relay for each signal, a slow acting relay associated with each line relay, means jointly controlled by a line relay and its associated slow acting relay and directional relay to govern the operation of the associated signal, a source of current located at each end of the track section, coding means associated with each current source adapted to normally supply train governing coded current to the rails of the section, a track relay responsive to coded current connected to the rails and arranged to be operated by the coded current supplied by one of said coding means only, a decoding relay, means associated with the track relay to energize said decoding relay in response to coded current supplied to the track relay a first circuit means controlled by the decoding relay to control the slow acting relay located at the same end of the section as the track relay and the line relay located at the opposite end of the section to thereby govern the operation of the signals, a second circuit means controlled by the decoding relay to govern the supply of coded train governing current at each end of the track section, and a third circuit means controlled by the decoding relay to control the two directional relays of the section. 105
14. In combination, a track section, an alternating current transmission line, a signal located at the entrance end of the track section, a line circuit associated with said signal, a polarized alternating current relay having one winding connected to said line circuit and a second winding constantly supplied with current from the transmission line, an auto-transformer located at the exit end of the section having a winding one half of which is the primary receiving current from the transmission line, means controlled by traffic conditions in advance to connect under certain traffic conditions one-half of the winding of said auto-transformer to the line circuit and under other traffic conditions to connect the other half of said winding to the line circuit to thereby effect a normal and a reverse position of the line relay, and operating circuits for the signal controlled by said line relay. 110
15. In combination, a track section, an alternating current transmission line, means located at the exit end of the section to supply to the rails train governing alternating current periodically interrupted at different rates, a line circuit, a polarized alternating current relay having one winding connected to said line circuit and a second winding constantly supplied with current from the transmission line, an auto-transformer having a winding one-half of which is the primary receiving current from the transmission line, means controlled by traffic conditions in advance of the section to connect under certain traffic conditions one-half of the winding of said auto-transformer to the line circuit and under other traffic conditions to connect the other half of said winding to the line circuit to thereby effect a normal and a reverse position of the line relay, and means controlled by the line relay for selecting the different rates of the periodically interrupted alternating current. 115
16. In combination, a track section over which traffic may move in either direction having a first and a second track circuit, a track relay for each track circuit responsive to train governing coded alternating current, means to normally supply each track circuit with said coded alter- 120
17. In combination, a track section over which traffic may move in either direction having a first and a second track circuit, a track relay for each track circuit responsive to train governing coded alternating current, means to normally supply each track circuit with said coded alter- 125
18. In combination, a track section over which traffic may move in either direction having a first and a second track circuit, a track relay for each track circuit responsive to train governing coded alternating current, means to normally supply each track circuit with said coded alter- 130

- nating current, a decoding relay for each track relay, means to energize said decoding relay in response to its track relay operated by coded alternating current, a signal located at each end 5 of the track section to govern traffic in opposite directions through the section, and means controlled by the decoding relays to control the operation of said signals and to control the supply of the coded alternating current to said 10 track circuits.
17. In combination, a track section, a track transformer located at the exit end of the section, a supply circuit to supply train governing coded alternating current to the track transformer, a track relay responsive to said coded alternating current located at the entrance end 15 of the section, a decoding relay, means associated with the track relay to energize said decoding relay when the track section is unoccupied 20 and the track relay thereby operated by the coded alternating current and to deenergize the decoding relay when the track section is occupied and the track relay thereby shunted, means controlled by said decoding relay to close said supply circuit when it is energized and to open said supply circuit when it is deenergized, and a line control relay responsive to traffic conditions in 25 advance of the section to render said decoding relay ineffective to open said supply circuit under 30 clear traffic conditions.
18. In combination, a track section over which traffic may move in either direction, means to supply current periodically interrupted to the traffic rails of the section, a track relay connected to the traffic rails and responsive to such 35 periodically interrupted current, a decoding relay, means to steadily energize the decoding relay when the track relay is operated by the periodically interrupted current, a normally energized 40 slow releasing relay responsive to traffic conditions of the track section and of an adjacent track section, a normally deenergized directional stick relay, a pick-up circuit for said stick relay including a front contact of the slow 45 releasing relay and a back contact of the decoding relay, and a circuit controlled by said stick relay for controlling the supply of interrupted current of another track section.
19. In combination, a track section over which 50 traffic may move in either direction, a source of track circuit current connected to the traffic rails at one end of the section, a track relay connected to the traffic rails of the section at the end opposite the source, a normally energized 55 slow releasing relay controlled by the track relay, a floater relay connected across the track leads of the source of track circuit current and normally energized, a normally deenergized directional stick relay, a pick-up circuit for the 60 stick relay including a front contact of the slow releasing relay and a back contact of the floater relay, and a signaling circuit closed only when said stick relay is energized.
20. In combination, a track section over which 65 traffic may move in either direction, a source for supplying current periodically interrupted and connected to the traffic rails at one end of the section, a track relay connected to the rails of the section at the end opposite the source and responsive to such periodically interrupted current, a decoding relay, means for steadily energizing the decoding relay when the track relay is operated by the interrupted current, a normally energized slow releasing relay controlled 70 by the decoding relay, a floater relay connected 75 across the track leads of the source of interrupted current and normally retained steadily energized, a normally deenergized directional stick relay, a pick-up circuit for said stick relay including a front contact of the slow releasing relay and a back contact of the floater relay, and a circuit controlled by said stick relay for controlling the supply of interrupted current of another track section. 80
21. In combination, a signaling circuit for rail-ways, a source for supplying said circuit with non-coded current, a code-following relay connected to the said circuit at a point remote from said source, a traffic controlled means located adjacent said relay to code the current supplied by said circuit to the code following relay, a decoding relay, means associated with the code following relay to energize the decoding relay in response to code operation of the code following relay, and traffic governing means controlled by said decoding relay. 85
22. In combination, a track section, a track circuit for the section including the track rails of the section, a source of current connected to the rails at one end of the section to at times supply said track circuit with non-coded current, a code following track relay connected to the track rails at the end of the section opposite the said source, traffic controlled means located adjacent the track relay and connected in the track circuit between the track rails and the track relay and adapted to code the non-coded current supplied to the rails, a decoding relay, means associated with the track relay to energize the decoding relay in response to code operation of the track relay, and traffic governing means controlled by the decoding relay. 90
23. In combination, a track section, a first source to normally supply alternating current periodically interrupted to the track rails at one end of the section, a track relay connected to the track rails at the opposite end of the section and alternately energized and deenergized by the periodically interrupted alternating current, traffic controlled means to disconnect the first source and to connect a second source to supply to the rails a non-interrupted alternating current, means located adjacent the track relay to periodically vary the impedance of the connection between the rails and the said track relay to effect an alternate energizing and deenergizing of the track relay when supplied with current from the said second source, and means controlled by the track relay when alternately energized and deenergized to disconnect the said second source and to connect the first source. 105
24. In combination, a track section, a track circuit including a source of steady alternating current connected to the rails at one end of the section, a track relay having a winding connected in series with an impedance unit to the rails at the other end of the section, an armature for said track relay adapted to engage one or the other of a pair of contacts, means for at times to periodically vary the impedance of said unit to effect alternate engagement of said armature with said pair of contacts in step with said periodic variations of the impedance unit, a controlling relay, means to energize said controlling relay in response to the alternating engagement of said armature with said pair of contacts, and traffic governing means controlled by said controlling relay. 110
25. In combination, a signaling circuit for 150

railways, a source to supply said circuit with alternating current, a relay connected to the circuit at a point remote from the source, an armature operated by said relay adapted to engage one or the other of a pair of contacts, means located adjacent said relay to at times periodically vary the value of the alternating current supplied by the circuit to the relay to effect alternate engagement of the armature with said pair of contacts, a controlling relay, means to retain said controlling relay energized in response to the alternating engagement of the armature with said pair of contacts, and traffic governing means controlled by said controlling relay.

26. In combination, a track section, a first circuit to normally supply coded current to the traffic rails at one end of the section, a track relay connected to the traffic rails at the opposite end of the section and responsive to such coded current in the rails, means responsive to a train entering the section at the end at which current is normally supplied to disconnect said first circuit and to connect a second circuit to supply non-coded current to the rails, means operated by the track relay when energized by non-coded current to open and close said second circuit to effect periodic energizing and deenergizing of the track relay, means controlled by the track relay when periodically energized and deenergized to restore the first circuit and to disconnect the second circuit.

27. In combination, a track section over which traffic may move in either direction, a first circuit to normally supply coded current to the rails at one end of the section, a track relay connected to the rails at the opposite end of the section and responsive to such coded current in the rails, a decoding relay, means to energize the decoding relay in response to the track relay periodically energized and deenergized and deenergize said decoding relay when the track relay is shunted, means responsive to a train entering the section at the end at which current is normally supplied to disconnect the first circuit and to connect a second circuit to supply the rails with non-coded current, means operated by the track relay when energized by said non-coded current to open and close said second circuit to effect a periodic energizing and deenergizing of the track relay to thereby reenergize the decoding relay, and means controlled by the decoding relay to restore the first circuit.

28. In combination, a track section over which traffic may move in either direction, a track transformer connected to the rails at one end of the section, a first circuit to normally supply the track transformer with alternating current periodically interrupted, a track relay connected to the rails at the opposite end of the section and responsive to such periodically interrupted alternating current, a decoding relay, means to energize the decoding relay when the track relay is periodically energized and deenergized and to deenergize said decoding relay when the track relay is shunted, means responsive to a train entering the section at the transformer end to disconnect the first circuit and to connect a second circuit to supply uninterrupted alternating current to the transformer, means operated by the track relay when energized by the uninterrupted alternating current to open and close said second circuit to effect a periodic energizing and deenergizing of said track relay

to thereby reenergize said decoding relay, and means controlled by the decoding relay for restoring the first circuit.

29. In an absolute permissive block signaling system for railroads, the method of controlling wayside signals as well as cab signals by means of periodically varied rail current, in which a detection code comprising current periodically varied at a given frequency is normally supplied to the track rails of a given section irrespective of traffic conditions in advance of said section for controlling the wayside signals, means governed by traffic conditions in said section being provided for transferring from said detection code to a cab signal control code which control code comprises current periodically varied at a frequency selected in accordance with traffic conditions in advance.

30. In combination, a section of railway track, a wayside signal associated with said section, means for normally supplying to the rails of said section a detection code for controlling said wayside signal, said code being supplied irrespective of traffic conditions in advance of the section and comprising rail current periodically varied at a given frequency, means governed by traffic conditions in said section for transferring from said detection code to a cab signal control code comprising current periodically varied at a frequency selected in accordance with traffic conditions in advance of said section, and means governed by other traffic conditions in said section for restoring from said cab signal control code to said detection code.

31. In an absolute permissive block signaling system for railroads, the method of detecting the presence of a train in a track section and governing the train in accordance with traffic conditions in advance of the section, in which current periodically varied in accordance with a given detection code is supplied to the track rails of the section irrespective of traffic conditions in advance of the section for controlling wayside apparatus to provide said train detection, means being provided effective upon the entry of a train into the section for transferring from said detection code to a selected one of a group of cab signal control codes employing periodically varied current, said selected code being determined in accordance with traffic conditions in advance of the section.

32. In combination, a section of railway track, two wayside signals for governing traffic in either direction through said section, a code following track relay connected with the rails at one end of said section for controlling said signals, means for supplying current to the rails at either end of the section, means for periodically varying the current supplied to the rails at the end of the section opposite said relay in accordance with a predetermined detection code for causing periodic operation of said relay to render effective the control of said wayside signals by the relay when said section is unoccupied, means effective when said section becomes occupied by a train entering from one or the other direction for periodically varying the current supplied to one or the other end of the section respectively in accordance with one of a group of cab signal control codes selected according to traffic conditions in advance of the section, and means governed by the cab signal control code effective when the train vacates said section for restoring said detection code to the section.

33. In an absolute permissive block signaling system for railroads, a section of railway track, a wayside signal associated with said section, means effective when said section becomes occupied for supplying the rails of said section with current periodically varied in accordance with one of a group of cab signal control codes selected in accordance with traffic conditions in advance, and means for applying a selected code of said group to the rails of said section irrespective of traffic conditions in advance of the section for train detection purposes when the section is unoccupied.
